UNITED STATES PATENT OFFICE.

JAMES CONTE, OF DES PLAINES, ILLINOIS.

GRADING AND SORTING APPARATUS.

1,377,399.

Specification of Letters Patent. Patented May 10, 1921.

Application filed June 9, 1920. Serial No. 387,550.

To all whom it may concern:

Be it known that I, JAMES CONTE, a citizen of the United States, residing at Des Plaines, in the county of Cook and State of Illinois, have invented a new and useful Improvement in Grading and Sorting Apparatus, of which the following is a specification.

My invention relates to apparatus for grading and sorting articles according to size, and more particularly to the design for an apparatus which will sort and grade onions and other vegetables, and also with changes in the dimensions, but not in the style or form of the grading elements, will grade nut meats, fruits and similar articles.

Onions, in particular, by reason of the dried stem or the sprout which extends from the body or bulb of the vegetable for different distances, some times much farther than the dimension of the bulb, and which stem or sprout is very often curved or curled, have heretofore been regarded so far as I am aware as practically incapable of satisfactory mechanical grading. Also with onions the grading operation must be so conducted that the stem or sprout is not detached from the bulb nor the outer skin ruptured nor the bulb bruised as the bruising or exposure of the inner layers of the bulb will hasten decay and the removal of the sprout, besides exposing the interior portions of the onion, will render the bulb useless for planting. At present the larger sizes of onions are sold for eating and various culinary purposes, an intermediate size is valuable chiefly for pickling, while the smaller sizes or sets are employed for planting. Different prices are obtained for these various sizes so that their separation or grading is highly desirable.

At present, so far as I am aware, a large proportion of the grading and sorting of vegetables and fruits is done by hand, which is a laborious operation and not at all reliable because the grading is not uniform. I am aware that blowers and mesh sieves and screens have been heretofore used for sorting and grading of onions and the like, but these are unsatisfactory, not only because the grading is not effectively accomplished, but also because the articles are bruised and damaged in the operation. Farmers or persons engaged in agricultural pursuits usually grade and sort by hand and only two sizes of onions are graded,—one inch in

diameter and over for market use and below one inch in diameter for pickling. Few farmers are able to separate the pickling size from what are known as the onion "sets" 60 and as these latter bring the best prices it will be seen that the farmers fail to realize as much as they should from the crop. With my apparatus I am able to sort the onions into as many grades as may be desired, and 65 especially into the market size, the pickling size and the "sets," and this is done automatically without damage or injury to the onions and the onions in each grade are uniform.

Among the divers objects of my invention 70 are the provision of a grading and sorting apparatus that will grade onions and like articles without damaging them that is simple in construction and dependable in operation; that is comparatively inexpensive 75 to manufacture so that it may be sold to the user at a relatively moderate price, and which is novel, compact and durable.

I prefer to attain the above-mentioned objects by means of the structure illustrated in 80 the accompanying drawings which form a portion of the present specification, and in which—

Figure 1 is a longitudinal side elevation of my improved sorting and grading apparatus. 85

Fig. 2 is a view similar to Fig. 1 showing the opposite side of the apparatus.

Fig. 3 is a top plan of the structure shown in Figs. 1 and 2. 90

Fig. 4 is a fragmental detail of the receiving ends of the screens and illustrating the manner of vibrating the same and the relation of the screen cleaning devices thereto, the view being a longitudinal section on line 95 4—4, Fig. 3.

Fig. 5 is a transverse section on line 5—5, Fig. 1, showing the means for vibrating the grading screens.

Fig. 6 is an enlarged fragmental section 100 of the hopper, taken on line 6—6, Fig. 3.

Fig. 7 is a bottom plan, enlarged, of a portion of one end of a grading element.

Fig. 8 is a fragmental detail of the manner of varying inclinations of the screen and 105 regulating the length of movement of the vibrator element.

In the drawings, similar reference characters have been employed to designate the same parts throughout the divers views. 110 The mechanism is mounted in and upon a frame consisting of four legs or standards

- 10, substantially united with the upper and lower side bars 11 and transverse end bars 12. In one end of the frame between the adjacent side bars is mounted the conveyer 5 table 13, the outer end thereof mounted so as to be tangent with the top of the conveyer table, is a conveyer belt pulley 14 having its bearings 15 horizontally adjustable on said frame by means of adjusting screws 16. 10 A conveyer belt or apron 17 passes around conveyer belt pulley 14, and the forward edge of the conveyer table 13 which is suitably rounded to permit of its easy passage thereover. 15 Mounted above the feeding end of the conveyer belt is an open bottom hopper 18. The walls of the discharge side or the side of the hopper from which the conveyer table extends is a suitable distance above the belt 20 to permit of the passage of the largest size of onion. In order to distribute the onions evenly over the belt and to prevent them from piling and also to prevent bruising the onions during this distribution, I have secured to the hopper wall above the belt a 25 flexible brush 19. This mechanism just described secures the uniform delivery of the onions or other articles to be graded to the belt and thereafter to the grading screens. 30 The grading screens just mentioned are of the "grizzly" type and preferably consist of a plurality of parallel disposed round rods or pipes 20 set a desired distance apart and suitably secured in any desired fashion 35 to two cross-bars 21 positioned on the backs of the rods or pipes and toward the respective ends of the rods. Pipes or rods of a comparatively large diameter are preferred as the jamming and bruising of the articles 40 between the rods is thereby prevented. The forward portions of the screen and rods and the cross-bars of each screen rest upon and against tie-rods 22 connecting the upper and intermediate portions of the adjacent standards 45 or posts 10, while the opposite or rear cross-rods of the screens are provided with centrally disposed rearwardly extending plates 23 which have recesses 24 in their extended edges that surround a vertically disposed vibrator-rod 25 and are supported 50 by shoulders or nuts 26 adjustably secured to said rod.
- Mounted, respectively, below each end of each screen transversely of the main frame 55 are four shafts 27 upon which are mounted sprockets 28 which carry parallel chains 29. Transversely of each pair of parallel chains is mounted one or more comb backs 30 upon which are teeth 31 which, when uppermost 60 with respect to the chains, enter between rods 20 of the respective screens so as to be moved substantially the length of said screens and to dislodge, without bruising, any article that may be caught between the 65 rods. Fixed just below the end of the up-

per screen between standards 10 is a chute 32 for directing the articles discharged from the adjacent end of the screen into a suitable receptacle such as a bag or basket positioned below the end of the chute. Below the lower 70 screen and also between the standards 10 is a chute 33 which is bent at right angles to direct the articles discharged from the adjacent end of the lower screen laterally to the side of the apparatus. A suitable receptacle may also be placed below and vertically alining with the lower screen to receive the articles that have passed between the spaced rods of the lower screen. It, of course, will be understood that more than 80 two screens can be employed, if desired, or that one of the screens described may be omitted without in any way interfering with the operation of the screen or screens employed. Secured to the ends of each cross-bar 21 are upwardly and outwardly inclined wooden strips 34 that serve as side frames for the screens so as to prevent articles escaping laterally from the sides thereof instead of being carried longitudinally to and 90 discharged from the lower end thereof. Mounted between the upper end of side-frames 34 of the lower screen or screens is a guard 35 preferably made from wire mesh which will prevent the articles from escaping over the upper ends of the lower screens. 95

Positioned between intermediate vertical standards 36 is a cross-bar 37 having a central upwardly extending tubular enlargement 38 which serves as a guide for the vertical reciprocation of vibrator-bar 25 upon the intermediate and upper portions of which are carried extensions, preferably, nuts 26 to carry screen-plates 23, hereinbefore described, so that by releasing and adjusting these nuts 26 up and down upon the vibrator bar 25 the relative inclination of the screen may be varied. The lower end of the vibrator bar 25 is screwed into a rectangular block 41 having a beveled lower edge 42 and 105 to prevent the block 41 twisting, right-angular pieces 43 are secured to the under face of cross-bar 37 the depending arms of which pieces act as guides for the sides of blocks 41. 110

Below cross-bar 37 and journaled in the intermediate vertical standard 36 is the main drive-shaft 44 of the machine which has intermediate its bearings the ratchet-wheel 45 the tooth-edge whereof coacts with the bevelled lower edge 42 of the rectangular block 41 to actuate or vibrate vibrator-bar 25, and thereby impart a quivering action to the screens. In order to adjust the stroke of vibrator-bar 25, adjustable and lock nuts 25^a 120 are provided upon the bar just above the tubular embossment 38 of the cross-bar, and nuts 25^a may be adjusted on the vibrator bar 25 so that they will not engage the upper end of the tubular embossment 28, thus 125 130

ing the vibrator bar 25 and the screens the full length of vibration, but upon adjusting nuts 25^a downwardly so that the lower face of the lower nut contacts the upper end of 5 embossment 38 the length of the vibratory movement may be controlled. This permits adjustment in the event of wear upon either block 41 or the ratchet. On one end of the main drive-shaft which extends beyond the 10 frame of the machine is mounted a drive-pulley 47 to be connected by means of a belt with any desired source of power. An idler pulley 48 is mounted loose on shaft 44 adjacent the drive-pulley so that by shifting the belt the machine may be stopped without turning off or stopping the power.

The opposite end of drive-shaft 44 also extends beyond its bearings in the frame where it is provided with a grooved pulley 20 49 carrying a belt 50 which rotates a blower fan 51 located between the screens for the purpose of blowing the small dirt, detached skins, and other matter from the articles being graded. The two forward shafts 27 are 25 extended beyond the main frame on the same side on which the drive and idler pulleys are located and alining sprockets 54 are mounted on these extended ends which are connected with an endless sprocket chain 55. Between the sprocket 54 on the lower shaft and the main frame is mounted another 30 sprocket 56, and upon the main drive-shaft 44 and alining with sprocket 56 is a sprocket 57. An endless sprocket chain 58 connects 35 sprockets 56 and 57 thereby furnishing power for driving the two pairs of parallel chains 29 and moving comb backs 30 carrying teeth 31 longitudinally of and between rods or pipes 20 of the screens.

40 Also secured upon the main drive-shaft 44 between the power and idler pulleys and the main frame is another sprocket 59 and arranged side by side with sprocket 57. Mounted preferably to the rear and above 45 main-drive-shaft 44 and transversely of the main frame is another shaft 60 which extends beyond the main frame on both sides. Mounted on one of the extended ends of shaft 60 so as to aline with sprocket 59 is a 50 sprocket 61 which is connected with sprocket 59 with an endless sprocket chain 62. Upon the opposite extended end of shaft 60 is a bevel gear 63 with which meshes another bevel gear 64 carried upon a shaft 65 the opposite end of which is provided with a worm 55 66 which meshes with and drives a worm-gear 67 carried by the conveyer belt pulley 14.

It will now be seen that the vibration or 60 trembling of the screens, the operation of the toothed combs for cleaning the screens and the movement of the conveyer belt is all accomplished from the movement of the main drive-shaft. It will also be seen that 65 the screen rods are of sufficiently large di-

ameter to prevent the jamming and bruising of any of the articles to be graded and that the vibration or trembling of the screens is not sufficiently violent to cause the damage of the articles. The toothed combs will effectively clean the screens of such onions or other articles which by reason of their stems or sprouts are not passed along the screens by their inclination and their movement. No articles can pass between the rods which are of greater diameter than the separation of the rods, and it will therefore be seen that I have provided an effective and simple apparatus for positively grading onions and other articles, no matter how irregular their outline, which will not damage the articles.

What I claim is:—

1. In a grading machine a movable grading element, a vibrator member having coactive relation with said grading element, a rotatable toothed wheel coacting with said vibrator member, and means for adjusting the latitude of movement of the vibrator member.

2. In a grading machine an inclined movable grading element, a vibrator member having coactive relation with said grading element, a rotatable toothed wheel coacting with said vibrator member, and means for adjusting the inclination of said grading element.

3. In a grading machine an inclined movable grading element, a vibrator member having coactive relation with said grading element, a rotatable toothed wheel coacting with said vibrator member, means for adjusting the inclination of said grading element, and separate means for adjusting the latitude of movement of the vibrator member.

4. In a grading machine a plurality of movable inclined grading elements, a vibrator member having coactive relation with each grading element, a rotatable toothed wheel coacting with said vibrator member, and means for adjusting the inclination of each grading element independent of each other.

5. In a grading machine a plurality of movable grading elements, a vibrator member having coactive relation with each grading element, a rotatable toothed wheel coacting with said vibrator member, and means for adjusting the latitude of movement of the vibrator member.

6. In a grading machine a plurality of movable inclined grading elements, a vibrator member having coactive relation with each grading element, a rotatable toothed wheel coacting with said vibrator member, means for adjusting the inclination of each grading element independent of each other, and separate means for adjusting the latitude of movement of the vibrator member.

7. In a grading machine a plurality of

grading elements disposed one above the other, a vibrator member having coactive relation with adjacent ends of each grading element, a suitable device coacting with the 5 vibrator member for actuating the same, and means for adjusting the latitude of movement of said vibrator member.

8. In a grading machine a plurality of grading elements disposed in inclined planes 10 one above the other, a vibrator member coacting with and supporting one end of each grading element, means carried by said vibrator member for adjusting the inclination of each grading element, and a suitable device coacting with the vibrator member for 15 actuating the same.

9. A grading machine comprising a supporting frame, a hopper mounted thereon, a conveyer belt movable longitudinally of 20 said frame below said hopper, a grading element of parallel rods secured in spaced relation, means supporting one end of said

grading element below the plane of the conveyer belt, combs movable in a path extending longitudinally between said grading 25 rods, a movable rod supporting the other end of said grading element and maintaining the same in an inclined position, a main drive-shaft, a toothed wheel mounted thereon and coacting with said rod whereby a 30 relatively rapid vibratory movement is imparted to said rod and the grading element carried thereby, means for limiting the latitude of vibration imparted by said toothed wheel, and means connected with said main 35 shaft whereby said movable elements are actuated.

Signed at Chicago, county of Cook and State of Illinois, this 4th day of June, 1920.

JAMES CONTE.
